WASTE AND OVERFLOW OUTLET AND
FITTING THEREFOR

William C. Groeniger, Columbus, Ohio, assignor
to John B. Pierce Foundation, New York, N. Y.,
a corporation of New York

Application June 16, 1939, Serial No. 279,560

3 Claims. (Cl. 4—199)

My present invention relates to waste and overflow outlets for baths, sinks, basins and the like, and more particularly to a unitary fitting for such waste and overflow outlets.

5 My present invention is adapted for use in connection with any receptacle for liquids in which it is desired to provide an outlet for discharging the liquid therefrom, and which will function to prevent the overflowing of the receptacle, and 10 prevent the level of the liquid in such receptacle from rising above a predetermined height. Also, my invention is adapted as a unit to be attachable to, or detachable from such receptacle, and the fittings to be used in conjunction with the waste 15 and overflow outlets may be readily assembled and disassembled while the waste and overflow outlet is in situ with respect to the receptacle.

A feature of my invention is an improved waste and overflow outlet fitting for a receptacle for 20 liquids, such as a bath tub.

A further feature of my invention is an improved waste and overflow outlet fitting for a receptacle such as a bath tub, and in which is housed the operating mechanism for a waste and 25 overflow valve mechanism.

Other features of my device will appear as the description of the invention progresses.

In the accompanying drawings:

Fig. 1 is a sectional side elevation of the waste 30 outlet end of a receptacle, such as a bath tub, and to which my present invention has been attached, the structure embodying the invention being shown in sectional elevation, and with the waste valve in closed position;

Fig. 2 is a sectional elevation through the waste outlet showing the waste valve in open position;

Fig. 3 is a front elevation of either Fig. 2, or the corresponding portion of Fig. 1, with the strainer plate broken away to show the outlet 40 valve operating mechanism, and with a portion of the outlet valve also being broken away, and

Fig. 4 is a sectional plan view taken on the line 4—4 of Fig. 1, and looking in the direction of the arrows.

45 Referring to the drawings, 10 designates a receptacle, such as a bath tub or other receptacle 10 for liquids such as water. The waste outlet end of the receptacle 10 is provided with a waste outlet opening 11 and an overflow outlet opening 12, arranged at the bottom of and adjacent to the top, respectively, of the bath tub 10.

In my present invention I attach to the bath tub 10 a waste and overflow outlet fitting, and attach the same in such a manner as to register 50 with the waste outlet 11 and overflow outlet 12.

The waste and overflow outlet fitting is designated by the reference numeral 13, and may be of any suitable material, but preferably a casting, such as a casting of brass, copper or the like. The waste and overflow outlet fitting 13 5 in the present instance is provided with a lateral outlet 14a and thus is particularly adapted to be utilized in connection with "above the floor" plumbing installations.

The waste and overflow outlet fitting 13 is provided at its upper end with a threaded opening 10 adapted to receive the external threads of a connecting member 14. The member 14 acts as a means for securely clamping the upper end of the waste and overflow outlet fitting 13 to the bath 15 tub 10. Between the outer surface of the bath tub 10 and the facing of material around the threaded hole in the waste and overflow outlet fitting 13 is placed a gasket or washer 15 of preferably flexible resilient material, and this 20 gasket or washer 15 assists in maintaining a fluid-tight joint between the upper end of the waste and overflow outlet fitting 13 and the overflow outlet 13 of the bath tub 10.

The connecting member 14 is hollow, as shown 25 in Figure 1, and is provided with internal threads which cooperate with external threads on a combined strainer and bearing member 16. The bearing is designated by the reference numeral 17 and is positioned with respect to the outer 30 circumference of the member 16 by the spaced radially extending spokes 18.

Rotatably mounted in the bearing is a shaft 19, provided with an offset portion 20, and with a shaft portion 21 arranged parallel to the shaft 35 19. The end of the shaft 19 extends outwardly of the bearing 17 to a point within the bath tub 10, and has secured to such end, by nut 22, an operating handle 23, and by means of which the shaft 19 may be rotated to move the parallelly 40 arranged shaft portion 21 thereof about the shaft 19 as an axis. Pivotally mounted on the shaft extension 21 is the upper end of an operating connecting rod 24, such rod being prevented from excessive longitudinal movement on the shaft extension 21 by the washers 25, and is prevented from accidental removal therefrom by the pin 26. The connecting rod 24 extends downwardly to a point to be hereinafter described.

The lower end of the waste and overflow outlet fitting 13 is provided—in addition to the side waste outlet member 14—with an internally threaded opening 27 to receive the external threads on a connecting member 28. The waste outlet 11 of the bath tub 10 has the material of 50 55

the bath tub formed on the frustum of a cone, as indicated by the reference numeral 29, and the angle of the frustum 29 is substantially equal to the angle of flare of the portion 30 of the externally threaded member 28.

Between the frustum of the cone 29 and the flared portion 30 of the member 28 is arranged a gasket 31 of preferably flexible resilient material, and as the member 28 is screwed into position with respect to the bath tub 10 and the waste and overflow outlet fitting 13, the gasket 31 will become pressed between the frustum of the cone 29 and the flared portion 30 of the member 28 to thereby establish a fluid-tight joint between the bath tub 10 and the waste and overflow fitting 13. The gasket 31 has the outer portion thereof folded over the flared portion 30 to be engaged by a member to be hereinafter described.

Fitting into the open flared end of the member 28 is the fitting 32. The outer portion of the fitting 32 is beveled to fit into the open flared mouth of the member 28 and the peripheral edge 33 engages with the folded-over portion of the gasket 31 so that when the member 32 is brought into close association with the member 28 a substantially fluid-tight joint is established therebetween.

The body of the member 32 is provided with a plurality of spaced perforations through which extends the cylindrical portion of T-shaped members 34, the T thereof being formed by the bar 35 extending from and engaging the inner face of the member 28 and a portion of the member 32. The end of each of the T-shaped members 34 is threaded to receive a nut 36 and by means of which the member 32 is firmly clamped in position with respect to the member 28.

Formed in the member 32 is a rectangular passage 37 and at the sides of the longitudinal passage are formed slideways 38, as clearly shown in Figure 2. The face of the outer peripheral edge of the rectangular passage 37 lies in a plane that lies at an angle to the slides 38 and forms a valve seat for a valve member 40.

Slidably mounted in the slideways 38 is a frame 39 which has secured to or formed integral therewith the valve 40, said valve 40 having its inner face, as viewed in the drawings, adapted to engage with and seat on, or be removed from the valve seat formed on the outer peripheral edge of the rectangular passage 37. The frame 39 is provided with a perforation 41 and through which extends an offset member 42 formed integral with and at the lower end of the connecting rod 24. Suitable means, as the washer 43 and pin 44, are employed to maintain the offset member 42 and frame 39 in operative relation with each other.

The construction just described is such that when the shaft 19 is rotated by the operating handle 29, the connecting rod 24 is moved upwardly and/or downwardly, and on viewing the structure shown particularly in Figures 1 and 2, it will be apparent that the frame 39 moves vertically upward and/or downward. The valve 40 however, although the same moves vertically upwardly and downwardly, does not move vertically either upwardly or downwardly with respect to the valve seat formed at the outer peripheral edge of the rectangular opening 37. On referring to Figures 1 and 2 it will be noted that the lower surface of the bottom of the bath tub 10 will be in substantial alignment with the lower edge of the rectangular opening 37 and that when the valve 40 is moved from the closed position shown in Fig. 1 to the opening position shown in Fig. 2

such valve member will move vertically upward but at an angle to the plane of the valve seat above referred to and will allow a free, clear passage for fluid that may be held within the bath tub 10. This is a particular advantage in clearing the bath tub 10 of foreign or solid matter as well as permitting all of the fluid to drain therefrom.

The tubular portion of each of the T-shaped members 34 is drilled and threaded to receive the 10 threaded ends of bolts 46, and such bolts are utilized for the purpose of clamping a strainer 47 over the valve 40 and over the waste outlet 11. Such a strainer however is easily removed should it be desired to manipulate or adjust the elements forming the waste outlet closure.

The entire structure above described is easily and readily attached to the waste outlet end of the bath tub 10, and may be removed therefrom at any time with a minimum of effort.

Whereas I have described my invention by reference to specific forms thereof, it will be understood that many changes and modifications may be made without departing from the spirit of the invention.

I claim:

1. An improved unitary waste and overflow outlet fitting for receptacles for liquid and the like having waste and overflow openings, comprising, in combination, a hollow body member provided at its ends with waste and overflow openings, connecting mechanism for securing the hollow body to the receptacle with the said openings thereof in alignment with the corresponding openings in the receptacle, a valve seat forming part of said connecting mechanism and having the seat thereof lying at an angle to the axis of said connecting mechanism, a valve associated with said valve seat, and means in the connecting mechanism for guiding said valve vertically into and out of engagement with the valve seat while maintaining the valve at all times in planes parallel to the plane of the valve seat.

2. An improved unitary waste and overflow outlet fitting for receptacles for liquid and the like having waste and overflow openings comprising in combination, a hollow body member provided at its ends with waste and overflow openings adapted to register with the corresponding openings in the receptacle, means for securing one end of the hollow body member to the receptacle with its opening in alignment with the overflow outlet opening in the receptacle, connecting means for attaching the other end of the hollow body member to the receptacle with its opening in alignment with the waste outlet opening of the receptacle, a conical valve seat structure associated with said connecting means and having a valve seat formed at the outer flared end thereof and lying within the limits of the receptacle, said valve seat lying in a plane at an angle to the vertical, guideways formed in said conical valve seat structure and forming a vertical track on each side of the valve seat structure, a valve associated with said valve seat, means on the valve cooperating with the guideways, whereby the valve is guided perpendicularly of the valve seat and simultaneously guided in a vertical direction, a shaft rotatably mounted in the connecting means at the waste outlet end of the fitting, a lever for rotating said shaft, and a connecting rod extending between said shaft and the valve, for operating said valve, whereby rotation of the shaft causes a recipro-

cating movement of the valve in a vertical direction with respect to the valve seat structure, and a vertical movement of the valve with respect to the valve seat.

5. 3. The combination with a receptacle provided with an outlet opening, outlet fitting means therefor comprising a hollow member having an opening at one end conforming generally to the contour of the outlet opening of the receptacle, 10 means for water-sealingly attaching said hollow member to the periphery of said outlet opening, a valve seat formed on said hollow means, said valve lying in a plane transverse to the axis of the outlet opening of the receptacle, a movable

valve member operatively associated with said hollow member and arranged to be seated upon said valve seat in its closed position, guideway means associated with said hollow member and with said movable valve member for guiding said 5 movable valve member simultaneously vertically and perpendicularly from its closed position with said valve seat to an open position, while maintaining said valve at all times parallel to the valve seat, and means for moving said movable 10 valve member to and from its closed and open positions at will.

WILLIAM C. GROENIGER.
